Charles H. Gage, Inventor

UNITED STATES PATENT OFFICE.

CHARLES H. GAGE, OF WASHINGTON, DISTRICT OF COLUMBIA.

SAFETY DEVICE.

Application filed April 15, 1925. Serial No. 23,364.

This invention relates to railway crossing gates.

In the accompanying drawings, forming a part of this specification, and in which like numerals are employed to designate like parts throughout the same.

Figure 1 is a top plan view of a road crossing provided with my device.

Figure 2 is a similar view to Figure 1, showing separate control systems.

Figure 3 is a side elevation of the gate and connections.

Figure 4 is a front elevation of the gate.

Figure 5 is section at 5—5 of Figure 3.

Figure 6 is a section through the channel track, with the lower portion of the gate shown in fragmentary section.

Figure 7 is a side elevation of the driving means for the gate.

Like reference characters indicate like parts throughout the several views and in the specification, in which there is shown in Figure 1, a pair of parallel railroad beds 2 and 3 and a cross vehicle road 4. Spaced apart from the railway 3 and crossing the road 4 is a gate 5, the gate 5 being suitably spaced from the adjacent rail of the road 3 so as to permit the easy accommodation of a vehicle between the railway and gate, so that in case a vehicle has passed the gate, it will not be injured by a passing train or be compelled to cross the railway. Spaced backward from the gate 5 upon the roadway 4 is a signal tower 6, preferably being spaced about 100 yards from the gate 5, the tower 6 being equipped with a semaphore 7, or other suitable means of warning a pedestrian or vehicle operator of an approaching train, the signals 7 and 8 being operated

from a suitable power unit 9, which likewise operates the gate 5 in the manner herein-after described. The power unit 9 is spaced from the gate 5 a distance slightly over that of the length of the gate 5, and the gate 5 is operated in the following manner: Carried beneath the gate 5 is a bar 10 carrying on its lower portion rack teeth 11, the bar 10 being embraced within a channel bar 12, the gate 5 being supported by rollers 13 interconnected with the gate by brackets 14, the rollers 13 riding upon tracks 15, the tracks 15 being spaced apart on each side of the channel 12. Carried within the power unit 9 is a suitable motor 16 having a shaft

17. Carried upon the shaft 17 is a small gear 18, meshing with a gear 19, the gear

19 being mounted upon a suitable shaft 20. Carried upon the shaft 20 is a pinion 21, the pinion 21 being beneath the rack 11 and co-meshing with the teeth of the rack 11. 60 The channel extends with an open top substantially twice the length of the gate, and from thence, as at 22, is of tubular form. Carried at the front of the gate 5 is a plow 23, beneath which plow 23 is a steel brush 24, the plow 23 being of sufficient width to clean the tracks 15 and to throw snow and the like therefrom to one side, the brush 24 following the plow and thoroughly scouring the tracks. Beneath the plow 23 is a 70 secondary plow 25 extending into the channel 12, the secondary plow being followed by a second brush 26, adapted to scour the channel 12. Upstanding beside the tracks 15 are posts 27 provided with brackets 28, the brackets 28 carrying rollers 29, the rollers 29 adapted to engage upon tracks 30, the tracks 30 carried one on each side of the gate 5 and substantially midway vertically of the gate 5, whereby in cooperation with the rollers 13, the gates are rigidly supported in a vertical and perfectly aligned position. Upon the approach of the train, suitable circuits are closed, and the motor 16, for each gate is set into action, and this 85 motor through the intermediate gearing, closes the gate. When the train leaves the crossing the motor operates upon the gate. It is obvious that the gear 21 may be turned by any suitable means. 90

Claims:

1. In a gate construction, a pair of spaced rails, a gate arranged between the rails to travel longitudinally thereof, flanged wheels traveling upon the rails and connected with the gate to support the same, a rack bar operating between the rails and attached to the bottom of the gate, and a rotatable gear engaging the rack bar. 95

2. In a gate construction, a pair of spaced rails, a channel bar extending longitudinally between the rails, a gate arranged between the rails to travel longitudinally thereof, a rack bar attached to the bottom of the gate and operating within the channel bar, 100 flanged wheels engaging the rails and connected with the gate to support the same, and a gear engaging the rack bar to advance the same. 105

3. In a gate construction, a track, a gate 110 to travel longitudinally of the track, wheels supporting the gate and traveling upon the

track, a plow carried by the gate to remove ice and the like from the track, and a brush arranged beneath the plow to sweep the track after it has been cleared by the plow.

5 4. In a gate construction, a track, a gate to travel longitudinally of the track, wheels supporting the gate and traveling on the track, a plow carried by the gate to clear the track, a channel bar extending longitudi-

dinally of the track, a rack bar attached to 10 the gate and operating within the channel bar, a gear engaging the rack bar to move the same, and a plow carried by the gate and operating within the channel bar to clean the same.

15 In testimony whereof I affix my signature.

CHARLES H. GAGE.
